(57) **CLAIM**

The ornamental design for a nail treatment case, as shown and described.

DESCRIPTION

FIG. 1 is a perspective view of the case, wherein the lid is shown in a closed position;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a bottom plan view thereof;

FIG. 7 is a perspective view of the case, wherein the lid is shown in an open position;

FIG. 8 is a perspective view thereof, wherein the nail treatment accessories are shown in phantom;

FIG. 9 is a top plan view thereof;

FIG. 10 is a front elevational view thereof;

FIG. 11 is a right side elevational view thereof, the left side elevational view being a mirror image thereof;

FIG. 12 is a rear elevational view thereof; and,

FIG. 13 is a bottom plan view thereof.

The broken line showing of the nail treatment accessories and bottom surface features is for illustrative purposes only and forms no part of the claimed design.
